UNITED STATES PATENT OFFICE.

JOHN McE. AMES, OF DONGAN HILLS, NEW YORK.

DOUBLE BODY-BOLSTER FOR RAILWAY-CARS.

No. 878,596.

Specification of Letters Patent.

Patented Feb. 11, 1908.

Application filed April 5, 1907. Serial No. 366,460.

To all whom it may concern:

Be it known that I, JOHN McE. AMES, a citizen of the United States, and a resident of Dongan Hills, in the county of Richmond 5 and State of New York, have invented certain new and useful Improvements in Double Body-Bolsters for Railway-Cars, of which the following is a specification.

The invention relates to improvements in 10 double body-bolsters for passenger cars, and it consists in the novel features and structure hereinafter described and particularly pointed out in the claims.

The object of the invention is to provide a 15 novel, durable, easily constructed and entirely efficient cast double body-bolster in one integral casting adapted for passenger cars and enabling the use of structural beams for the center or draft sills and side sills 20 in lieu of wooden center and side sills commonly used in the construction of passenger cars.

The invention will be fully understood from the detailed description hereinafter 25 presented, reference being had to the accompanying drawings, in which:

Figure 1 is a top view of a cast double body-bolster embodying my invention, the center sills being omitted and the side-sills being 30 shown in horizontal section; Fig. 2 is a side elevation, partly broken away, of same, one longitudinal half of the bolster being in central vertical section and the center and side sills being shown in position and in section on 35 the bolster; Fig. 3 is a vertical transverse section through the bolster on the dotted line 3—3 of Fig. 2; and Fig. 4 is a side elevation of about one-half of one side of a bolster embodying a modification of the invention, 40 this modification residing mainly in the proportions of the parts and in carrying the top plates of the bolster side-frames through instead of over the car center-sills.

In the drawings, 10 designates the side- 45 frames of the double body-bolster, 11 a central beam extending in line with the length of the car and connecting said side-frames, 12 end-beams connecting said side frames at their end portions, and 13 beams connecting 50 said side frames at points between the central beam 11 and end-beams 12, the whole being in one integral casting and said side frames being approximately in their body portion of I-shape in cross-section and formed 55 integrally upon the upper surfaces of their end portions with the vertical flanges 14

which strengthen the structure and afford means for the proper securing of the car side-sills and bolster together.

The side-frames 10 are deeper at their middle than at their end portions, and the middle portions of the top horizontal flanges of said side-frames are on about the same horizontal plane with the general upper surface of the central connecting beam 11, while at 60 their end portions the said flanges incline downwardly and merge into the end beams 12, as shown in Fig. 2. The flanges 14 are formed upon the end portions of the top horizontal flanges of the side-frames 10 and to 65 these flanges 14 are secured angle plates or knees 15 to which the car side-sills 16 may be riveted. The ends of the top and bottom flanges of the side-frames 10 merge into the 70 end-beams 12, which are triangular in cross-section, as shown in Fig. 2, and afford seats for the side-sills 16, the lower flanges of said side-sills resting upon said beams 12 and passing below the outer ends of the angle-irons or knees 15.

The side-frames 10 are formed at opposite 75 sides of each end of the central beam 11 with recesses 17 to receive the center or draft-sills 18, and at the base of said recesses 17 and extending beyond the outer side edges of the 80 same, the side frames 10 are formed integrally with horizontal flanges 19 between which and the main lower flanges of said side frames are vertical laterally extending flanges 20. The flanges 19 afford durable 85 seats for the sills 18 and the recesses 17, in the construction shown in Fig. 2, are equal in depth to the height of said sills. The flanges 19 extend horizontally on both sides of the web of the side frames and afford adequate seats for the center sills 18, which may 90 be secured to the webs of the side frames by means of the angle-irons or knees 21 riveted to said webs at opposite sides of each recess 17. The bottom flanges of the side-frames 10 are widened at their central portions, as 95 at 22, and the flanges 19 extend outwardly at the base of the recesses 17 to substantially the full width of said widened portions 22 and thence incline inwardly to the webs of 100 said side-frames. At the inner sides of the side-frames 10, the flanges 19 are joined to the web of the central beam 11 by gusset-flanges 23, which with the flanges 19 create a very durable structure at the adjoining 105 connected web-portions of the side frames 10 and said beam 11.

The connecting beam 11 comprises a main horizontal upper flange 24, a lower flange 25 and a vertical web 26 connecting these flanges, the whole forming approximately in 5 cross-section a beam of I-shape whose ends are integral with the side-frames 10. Intermediate the flanges 24, 25 of the beam 11 is formed a central cylindrical section 27 for the usual center-pin, and centrally below the 10 flange 25 is formed the body center-bearing 28.

The beams 12 connecting the end portions of the side frames 10 are triangular in cross-section, and the connecting beams 13 are preferably of I-shape in cross-section, as 15 shown in Fig. 2. At their central portions I preferably widen the lower flanges of the beams 13, as at 29, and form vertical webs 30 connecting the members of said beams, thereby strengthening said beams 13 at their 20 central portions.

The entire double body-bolster, less the top-plates 31, is formed in one integral casting ready to receive the center and side-sills, and the said bolster has been designed with a 25 view of securing an efficient distribution of the metal throughout the same and of producing a structure capable of ready manufacture and of great strength and durability.

The top-plates 31 are riveted to the top 30 flanges of the side-frames 10 and, in the construction shown in Figs. 1, 2 and 3, extend continuously across the recesses 17 and over the center-sills 18.

In Fig. 4 I illustrate a modification in the 35 proportions of the parts of the bolster, this modification residing in lessening the depth of those portions of the bolster located above the horizontal laterally extending flanges 19 so that the center-sills may project above the side-frames 10, as shown. In 40 this construction the top-plates on the side-frames extend through the webs of the center-sills.

What I claim as my invention and desire 45 to secure by Letters-Patent, is:

1. A cast double body-bolster comprising two side-frames and a central beam connecting the same and integral at its ends therewith, said side frames being formed through 50 their upper portions at opposite sides of each end of said beam with independent recesses and horizontal flanges at the bases thereof, said recesses being adapted to closely receive car center-sills and the webs of said 55 side frames at opposite sides of said recesses affording means for securing said sills; substantially as set forth.

2. A cast double body-bolster comprising two side-frames and a central beam connecting the same and integral at its ends therewith, said side frames being formed through 60 their upper portions at opposite sides of each end of said beam with independent recesses and horizontal flanges at the bases thereof, 65 said recesses being adapted to closely receive

car center-sills and the webs of said side frames at opposite sides of said recesses affording means for securing said sills, combined with top plates secured upon said side frames and engaging said sills; substantially 70 as set forth.

3. A cast double body-bolster comprising two side-frames and a central beam connecting the same and integral at its ends therewith, said side frames being formed through 75 their upper portions at opposite sides of each end of said beam with independent recesses and horizontal flanges at the bases thereof, said recesses being adapted to closely receive car center-sills and the webs of said side 80 frames at opposite sides of said recesses being provided with knees extending from both sides of the webs for securing said sills, combined with top plates secured upon said side frames and engaging said sills; substantially 85 as set forth.

4. A cast double body-bolster comprising two side frames of I-shape and a central beam connecting the same and integral at its ends therewith, said side frames being formed 90 through their upper portions at opposite sides of each end of said beam with independent recesses and horizontal flanges at the bases thereof, said recesses being adapted to closely receive car center-sills and the webs of said 95 side frames at opposite sides of said recesses affording means for securing said sills, combined with top-plates riveted upon said side frames and extending across said recesses and over the tops of said sills; substantially 100 as set forth.

5. A cast double body-bolster comprising two side frames of I-shape and a central beam of I-shape connecting the same and integral at its ends therewith, said side frames being 105 formed through their upper portions at opposite sides of each end of said beam with independent recesses and horizontal flanges at the bases thereof, said recesses being adapted to closely receive car center-sills and the webs 110 of said side frames at opposite sides of said recesses being provided with knees extending from both sides of the webs for securing said sills, combined with top plates riveted to said side frames and crossing said recesses; 115 substantially as set forth.

6. A cast double body-bolster comprising two side frames of I-shape and a central beam connecting the same and integral at its ends therewith, said side frames being 120 inclined downwardly at their end portions to afford seats for metal side-sills and formed through their upper portions at opposite sides of each end of said beam with independent recesses and horizontal flanges at the 125 bases thereof, said recesses being adapted to closely receive car center-sills and the webs of said side frames at opposite sides of said recesses affording means for securing said sills, combined with top plates riveted on 130

said side frames and crossing said recesses; substantially as set forth.

7. A double body-bolster comprising cast side frames of I-shape, an integral central beam connecting the same, and beams connecting said side frames at their ends, said side frames being recessed to receive car center-sills and inclining downwardly at their end portions toward said end beams 10 and having integral flanges affording means for securing car side-sills; substantially as set forth.

8. A double body-bolster comprising cast side frames of I-shape, an integral central beam connecting the same, beams connecting said side frames at their ends, said side frames being recessed to receive car center-sills and inclining downwardly at their end portions toward said end beams and having 20 integral flanges affording means for securing car side-sills, and top-plates secured to said side frames and extending continuously across the recesses therein; substantially as set forth.

25 9. A double body-bolster comprising in one integral casting two side frames, a central beam connecting the same, end-beams of angle-iron shape connecting said side frames at their ends, and beams connecting said side frames between said central and end beams, said side frames at their ends being inclined downwardly and formed with vertical flanges to which said side-sills may be secured, and said side frames being formed 35 through their upper portions at opposite sides of each end of said central beam with independent recesses and horizontal flanges at the bases thereof, said recesses being adapted to closely receive car center-sills and 40 the webs of said side frames at said recesses affording means for securing said sills, combined with top plates riveted upon said side frames and crossing said recesses; substantially as set forth.

45 10. A double body-bolster comprising in one integral casting two side frames, a central beam connecting the same, end beams of angle-shape connecting said side frames at their ends, and beams connecting said side 50 frames between said central and end beams, said side frames being recessed to receive car center-sills and formed with vertical flanges adjacent to said end beams, which afford seats for car side-sills, combined with top-

plates secured upon and extending continuously across the recesses in said side frames; substantially as set forth.

55 11. A double body-bolster comprising in an integral casting side frames of I-shape and a central connecting beam, said side frames at their end portions having their upper and lower flanges extended on converging lines and being formed with vertical flanges within the depressions formed by the downward inclination of said top flanges, and said side 60 frames being recessed to receive car center-sills and formed at the base of the recesses with horizontal flanges; substantially as set forth.

65 12. A double body-bolster comprising in an integral casting side frames of I-shape and a central connecting beam, said side frames at their end portions having their upper and lower flanges extended on converging lines and being formed with vertical flanges within 70 the depressions formed by the downward inclination of said top flanges, and said side frames being recessed to receive car center-sills and formed at the base of the recesses with horizontal flanges; combined with top- 75 plates secured upon and extending continuously across the recesses in said side frames; substantially as set forth.

80 13. A double body-bolster comprising in one integral casting side-frames having top and bottom flanges and connecting web and a central connecting beam having top and bottom flanges and connecting web joined to said side-frames, said side-frames being recessed through their upper portions at each 85 side of each end of said central beam to receive car center-sills and formed at the base of the recesses with horizontal flanges affording seats for said sills, and said horizontal flanges at the inner side of said frames being 90 joined integrally with the web of said beam intermediate its top and bottom flanges by gusset flanges, combined with top plates riveted on said side frames and crossing said recesses; substantially as set forth.

95 100 Signed at New York city, in the county of New York, and State of New York, this 4th day of April A. D. 1907.
